UNITED STATES PATENT OFFICE.

DAVID BOGEN, OF NEW YORK, N. Y.

DESIGN FOR A SOUVENIR.

55,408.

Specification for Design.

Patented June 8, 1920.

Application filed December 20, 1919. Serial No. 346,390. Term of patent 3½ years.

To all whom it may concern:

Be it known that I, DAVID BOGEN, a citizen of the United States, residing at New York, in the county of New York and State of New York, have invented a new, original, and ornamental Design for a Souvenir, of which the following is a specification, reference being had to the accompanying drawing, forming part thereof.

Figures 1, 2 and 3 are respectively a front view, side view, and a rear view showing my design.

I claim:—

The ornamental design for a souvenir as shown.

DAVID BOGEN.
